(57) **CLAIM**

The ornamental design for a shaft with a control lever for a self-balancing personal transporter, as shown and described.

DESCRIPTION

1. Shaft with a control lever for a self-balancing personal transporter

1.1 is a front elevation view of a shaft with a control lever for a self-balancing personal transporter showing our new design;

1.2 is a left side elevation view thereof;

1.3 is a rear elevation view thereof;

1.4 is a front, top, left side perspective view thereof; and

1.5 is an enlarged top plan view thereof.
